UNITED STATES PATENT OFFICE.

FRANKLIN P. MILLER, OF BLOOMFIELD, NEW JERSEY.

TOOL-HOLDER.

No. 811,786.

Specification of Letters Patent.

Patented Feb. 6, 1906.

Application filed March 15, 1904. Serial No. 198,247.

To all whom it may concern:

Be it known that I, FRANKLIN P. MILLER, a citizen of the United States, residing at Bloomfield, in the county of Essex and State 5 of New Jersey, have invented certain new and useful Improvements in Tool-Holders, of which the following is a specification.

My invention relates to tool-holders for lathes and other machines where a cutting-tool has to be supported; and it consists of a block contracted toward one or both ends, having one or more side sockets with means for holding a tool and securing it in desired positions therein and adapted to also support 15 the carrier for a boring-tool, as fully set forth hereinafter and as illustrated in the accompanying drawings, in which—

Figure 1 is a side view of a holder for a single tool; Fig. 2, an edge view of the same; 20 Fig. 3, a plan view; Fig. 4, a perspective view of a double holder or one adapted for supporting two tools. Fig. 5 is a side view of a holder shown in Fig. 4; Fig. 6, a plan showing the holder of Figs. 4 and 5 in its relation to the 25 work in different positions; Fig. 7, a side view of a carrier for a boring-tool adapted for use with the holder; Fig. 8, the same in part section applied to a holder and carrying the boring-tool; Fig. 9, a plan of a carrier and its 30 boring-tool.

The tool-holder consists, essentially, of a heavy block A, which may be adapted for the support of one or more tools B and which has an elongated recess 1 for the reception of the 35 usual post C, which may be applied to the bed or movable carrier D of a lathe. The block is beveled or contracted at one or both ends—that is, it is tapered in a plane transverse to the axis of the post—and at one or 40 more sides of this block are sockets 3, each of which is inclined upward and outward to permit the tool to be presented at an angle with its edge against the material, while the holder occupies a low position and is therefore more 45 solid and rigid. Each socket has a rounded lower face 4, adapted to the rounded lower face of a shoe 5, which may therefore be set at different angles, according to the angle at which the tool B is to be set, the said tool 50 resting upon the upper face of the shoe within the socket and being secured after adjustment by means of any suitable securing device—as, for instance, a set-screw 6.

In the construction shown in Figs. 1, 2, 3 55 the holder is single—that is, adapted for the reception of but one cutting-tool. In Figs.

4, 5, and 6 is shown a construction adapted for receiving two tools. In either case it will be seen that by providing a heavy block with a socket at one side it is possible to make use of a tool consisting of a plain block of steel capable of being shaped without forging and which will be supported almost to its cutting end within the socket of the block so as to be rigid and unyielding, avoiding the objections incident to the spring of the tool or the holder. I can therefore use a very much smaller amount of metal, as the tool as it wears may be ground and reground and fed forward until but a small portion of the stock 70 remains. The common forged tool is very wasteful of both labor and steel, as the forging shapes only a small part of the stock, and this alone is used for cutting purposes.

A heavy block of metal contracted toward one or both ends, as described, and having a recess, which may be round or elongated, adapted to receive the post of a lathe, not only affords a firm support for the tool, but owing to its pointed end permits the tool to 80 be supported at points close to the head or shoulder of the lathe and to be introduced into parts of the work where heretofore it has been necessary to employ tools supported so far from their ends that the spring of the tool 85 has produced imperfect work, resulting in the breaking of the tools and limited speed of operation. By the use of a pointed block of the character described with the socket at one side the tool can be supported almost to 90 its cutting edge by a support which is practically rigid and unyielding, and when the block has an elongated recess the holder may be shifted upon the post to carry the tool back and forth and present it to the work at 95 any desired angle.

When the holder is double, as shown in Figs. 4 and 6, it may be swung upon the post to different positions, as indicated in Fig. 6, bringing either tool into operation upon the 100 work. In this case the two socketed sides meet at an angle, so that either tool can be brought more nearly parallel with the article being cut or with the axis of the lathe than would be possible if the tools were in line. 105

While the holder is adapted especially for use with tools made of simple bars ground to shape, it may of course be employed in connection with various forms of tools.

For use in connection with boring-tools I 110 employ a socketed carrier E, (shown in Figs. 7, 8, and 9,) the said carrier having a recess 8

to receive the stem 9 of the boring-tool F and with set-screws or other securing devices 10, and at the side of this carrier is a wing 12, which is preferably inclined, as shown, and which may be inserted in the socket of the holder A and rest upon the shoe and be adjusted to different angles and secured in the same manner as the tool B. It will be obvious, of course, that this carrier E may be of different shapes with sockets of different shapes, according to the character of the boring-tool to be used.

Without limiting myself to the precise construction shown, I claim—

15 1. A tool-holder consisting of a block recessed to receive a post to secure it to the bed or carrier of a lathe, tapered in a plane transverse to the axis of the post, and provided

with a side recess and means to secure a tool in an inclined position therein, substantially 20 as set forth.

2. A tool-holder consisting of a block recessed to receive a post tapered at each end in a plane transverse to the axis of the post, forming converging side faces, with an inclined recess in each face, and means for securing a tool therein, substantially 25 as set forth.

In testimony whereof I have signed my name to this specification in the presence of 30 two subscribing witnesses.

FRANKLIN P. MILLER.
